ELECTRON DISCHARGE DEVICE

Donald L. Benedict, Manhasset, N. Y., assignor to
 Sylvania Electric Products, Inc., a corporation
 of Massachusetts

Application September 29, 1945, Serial No. 619,289

16 Claims. (Cl. 315—39)

1

My invention relates to electron discharge devices and more particularly to electron discharge devices which have particular application to the production of ultra high frequency power oscillations such as one including an anode and a spaced cathode with magnetostatic and electric fields in the space between the anode and cathode.

Heretofore various types of electron discharge devices have been employed for producing ultra high frequency oscillations, one such type including an anode with a cathode spaced from the anode and with a magnetic means producing a field in the region between the cathode and anode, the direction of the magnetic field being substantially parallel with the axis of the electrodes and with an electric field polarizing the anode positive with respect to the cathode. These general principles of such tubes which are commonly called magnetrons are discussed in numerous text books as "Ultra High Frequency and Techniques" by Brainard, Koehler, Reich, and Woodruff (Van Nostrand), 1942 edition, pages 310-324.

It is to be noted that electron discharge devices of this type normally called magnetron tubes are of several kinds according to their performance, those most commonly encountered being the low field magnetron, the transit time magnetron, and the negative resistance magnetron. Of these the first two types have been adapted to use at ultra high frequencies, while the other is not commonly used at frequencies above 10^9 cycles per second. The electron discharge device of the low field magnetron type, to which my invention finds efficient application, is characterized in that the strength of the magnetic field applied to the tube ordinarily is lower than that which would be required to produce a rotational frequency of electrons equal to the circuit frequencies.

Included among those classes of magnetrons noted above are devices in which the anode is comprised of more than two pieces, such as the split type of anode magnetron described by W. Dallenbach in U. S. Patent 2,128,237, patented August 30, 1938, and the low field magnetron described by Haban and Gerth in U. S. Patent 2,151,912, patented March 28, 1939. Another type of high frequency electronic apparatus which employs an anode of a plurality of members is described in Ramo & Blewett, Patent No. 2,247,077, patented June 24, 1941.

One of the difficulties, however, with electron discharge devices of the type mentioned above is

5 that they are not arranged to operate over a controllable range in frequencies beyond that which may be obtained by the adjustment of the fields and the characteristics of the coupling device, such change being over a comparatively narrow range and at a considerable sacrifice of power generated as the frequency is made to deviate from that at which optimum performance for that particular device is attained.

10 It is therefore an object of my invention to provide an improved electron discharge device which employs magnetic and electric fields within the space between the anode and the cathode with an improved structure including a cavity resonator so that the device may be made to operate efficiently over a relatively wide range of frequencies.

15 A further object of my invention is to provide an improved electron discharge device of the magnetron oscillator type which is tunable over a relatively wide range of frequencies and which is operable with relatively low electric and magnetic fields.

20 A still further object of my invention is to provide a tunable ultra high frequency magnetron which is relatively simple in construction and adaptable to quantity production.

25 A still further object of my invention is to provide a relatively simple tunable magnetron adapted to operate in a cavity resonator in which the frequency of operation is relatively independent of fluctuations in magnitude of the electric and magnetic fields.

30 Further objects and advantages of my invention will become apparent from the following description referring to the accompanying drawing, and the features of novelty which characterize my invention will be pointed out with particularity in the claims annexed to and forming a part of this specification.

35 Referring to the drawing:

Fig. 1 is an enlarged longitudinal sectional view through an electron discharge device embodying features of my invention and which view is taken along the line 1—1 of Fig. 2;

40 Fig. 2 is a transverse sectional view taken along the lines 2—2 of Fig. 1;

Fig. 3 is a top plan view of the cathode sleeve and part of Fig. 1;

45 Fig. 4 is a view partly in elevation, partly in longitudinal central section of the cathode sleeve employed in the construction of Fig. 1;

50 Fig. 5 is an end view of the electron discharge device as looking from the top of Fig. 1 but drawn to a much smaller scale;

Fig. 6 is a side view in elevation of one of the anode members employed in the construction of Fig. 1;

Figs. 7 and 8 are face and end views in elevation of a cavity resonator and its supporting means which is adapted to be employed with the electron device as illustrated in Fig. 1;

Fig. 9 is a fragmentary sectional view illustrating a modification of my invention with a cathode mounted slightly off center with respect to the anode;

Figs. 10 and 11 are fragmentary diagrammatic illustrations showing developmental views of the anode of further modifications of my invention, Fig. 10 showing a finger on one of the members being longer than the others, and Fig. 11 showing one of the fingers as being narrower than the others.

Fig. 12 is a sectional view along the lines 12—12 of Fig. 7 with certain of the parts shown in full, with the magnetic means and the electrical means shown diagrammatically and with the envelope partly broken away to illustrate more clearly the internal parts thereof, and Fig. 13 is a face view as seen from the underside of Fig. 12, the parts being shown in section on the line 13 of Fig. 12.

Referring to the drawing, and more particularly to Fig. 1, I have illustrated an electron discharge device including an envelope made of any suitable material such as glass comprising three sections, the first section indicated by the numeral 1 being the lower or header section, the central section being indicated by the numeral 2, and the top section or dome section being indicated by the numeral 3, the three sections being separated by and sealed to discs 4 and 5 which may be formed of any suitable conductive material such as oxygen-free copper. Within the envelope there is provided a thermionic cathode 6 which is also provided with a heating element 7 which is supported within the cathode between ceramic members 8 and 9. Surrounding at least a portion of the cathode structure 6 I provide an anode structure which includes a first anode member 10 and a second anode member 11. As is illustrated more particularly in Fig. 6 each of the anode members includes a ring-like portion 10a with a plurality of finger-like members, 10b, projecting therefrom substantially in the surface of a cylindrical shell. Each portion 10a constitutes a circular connector for alternate conductive fingers 10b. In order to provide a convenient arrangement for supporting the anode members, the anode member 10 within the envelope is connected to the disc member 4 through the ring member 10a which is attached in any suitable manner such as by soldering to a flange portion 12 which is integral with the disc 4 and which extends internally of the envelope 3. Lugs 13 may be provided for supporting the ring against the flange until it is soldered.

It can also be seen from an inspection of the drawing that the anode member 11 is similarly supported and connected to the lower disc member 5. The anode members 10 and 11 are so formed and their extending fingers have such a length and width with respect to the space between adjacent fingers 10b that when they are positioned in the manner illustrated in Figs. 1 and 2, they will be interdigitated or intermeshed with substantially equal spacing between adjacent fingers, the fingers lying in the surface of a right circular cylinder with its axis substantially coaxial with respect to the cathode axis. Any

suitable number of digits may be employed for the anode, and in the illustrative embodiment of my invention each of the anode members has eight digits or fingers.

Any suitable arrangement may be provided for connecting the heater filament 7 to a heater circuit and in the arrangement illustrated in the drawings I provide lead-in wires 14 and 15 which may be made of any suitable alloy, such as a chromium-nickel-iron alloy used for sealing to glass. The lead-in wires may be positioned in any desirable relation and as shown lead-in wire 14 constitutes a connection and a support through tabs 16 and 17 for the cathode 6, and through a tab 18 for one end of the heater 7, while lead-in wire 15 and tab 19 constitute the connection and support for the other end of the heater.

The anode fingers may be interdigitated to any suitable amounts and in the arrangement illustrated in Fig. 1 they are interdigitated over a part of their length, the extremities being indicated by the planes 20 and 21. The planes serve also to indicate the approximate length of the band of electron emissive coating 22 ordinarily used on the cathode, but in some cases the band is somewhat longer, while for a low power or for continuous non-pulsed operation, it is frequently advantageous to make the coating band much shorter than that indicated by the planes 20 and 21.

Flanges 24 and 25 on the cathode serve for the purpose of conserving the energy by confining the electron discharge within the interdigitated region of the anode.

In order to provide a tunable resonant circuit which is connected between the anode portions 10 and 11 I provide, as illustrated in Figs. 12 and 13, a cavity resonator 26 which includes a box-like portion 27 and a plate or cover portion 28. The envelope may be supported in the opening in the cavity with the discs against shoulders, a relatively tight connection being provided through a reinforcing ring 29 on one of the discs and screws 30. A frame member 31 is in turn attached to the cavity resonator. Brackets or frames 32 and 33 are provided and they are attached to the cavity resonator through screw 31a.

In order to provide an arrangement for the conduction of power from the electron discharge device during its operation I provide a concentric line including a tube 34 within which is contained a line 35 which is connected at its inner looped end 36 to the cavity resonator.

When my electron discharge device is employed as is illustrated in the drawing a magnetic field is employed which magnetic field may be produced in any suitable manner such as through a magnet indicated generally by the numeral 37. As will be understood by those skilled in the art the pole pieces of the magnet produce a magnetic field which is substantially parallel with the longitudinal axis of the anode and cathode. An electric field is provided through a source of direct current power indicated by the numeral 38, the positive side being connected to the cavity resonator through a conductor 39 and the negative side is connected to the cathode through a line 40. A source of heater power for the cathode heater 7 may be obtained from a source of power through the heater supply transformer 41.

In order to provide an arrangement for varying the tuning of the electron discharge device a plurality of tuning screws 43 is provided each of which cooperates with a tapped bore or guide 44 in the two parts of the cavity resonator 26. It will

be noted in the illustrative embodiment of my invention seven tuning screws are placed at 45° intervals except that where the line 35 is fitted into the cavity resonator there is no tuning screw at this position. It will be understood however that both the form and number of the tuning screws may be varied to suit such factors as design details of the tube in relation to the cavity resonator dimensions hence, for example, I may use five or nine screws and may place on the inner end another block which may contact the upper and lower ends of the cavity either conductively or insulatingly; or I may use other forms of suitable resonators.

Operation of my improved electron discharge device is as follows: It will be understood that upon application of power through the cathode heater circuit and with an electric field and a magnetic field within the space between the anode and cathode that electrons will leave the cathode and be drawn towards the anode. This movement, however, causes them to interact with the magnetic field resulting in the precession of the electrons in one direction about the cathode. As the electrons approach the anode their velocity increases but due to the action of the magnetic field their motion is substantially tangential to the inside cylindrical surface of the anode. Thus all the electrons in the vicinity of the anode tend to move in the same direction with high velocity and are in position to be acted upon by the high frequency electric field which exists between adjacent fingers of the anode. The influence of this high frequency field causes a bunching action of the electrons into spaced groups. These spaced groups tend to precess about the cathode with such phase and angular velocity as to be opposed by the instantaneous fields between adjacent teeth of the anode and thus to deliver high frequency power to the anode system.

There are several different modes or ways in which oscillation may take place within the device. In the simplest mode, or π mode, to be described later, there are half as many groups of electrons precessing around the cathode as there are fingers on the anode. The angular velocity of rotation in radians per second of a group of electrons is

$$\text{Output frequency} \times 4\pi$$

Number of fingers

In the π mode of oscillation, just mentioned, all of the fingers in one group such as those connected to the anode member 10a are simultaneously at one potential, while all the fingers in the other group, such as those connected to the anode member 11b are simultaneously at another potential. The potentials of the two groups vary sinusoidally with respect to each other at the output frequency of the device.

It is to be noted that one of the groups of fingers is attached cylindrically to disc 4 while the other group of fingers is attached similarly to disc 5. Thus the potential of disc 4 with respect to disc 5 varies sinusoidally due to this difference in potential. Instantaneous current tends to flow radially along the walls of the cavity resonator from one disc to the other. It is the flow of electric current from one set of fingers through the corresponding disc such as 4 through the cavity resonator, back through disc 5 and onto the other set of fingers that constitutes the high frequency oscillation in the cavity resonator. In this mode of oscillation current flows radially

outward in all directions through the inner surface of disc 4 while flowing inwardly in all directions through the inner surface of disc 5. The direction of flow, of course, reverses itself at twice the frequency of the output. At any instant in time within the cavity resonator the electric field strength due to instantaneous difference in potential between the top and bottom of the cavity resonator is substantially independent of the angular position about the anode axis. The electric field strength at any instant is zero at the outer periphery of the cavity resonator space and increases monotonically in absolute value toward the anode. The π mode is the first of a series of radial modes, a radial mode being one in which there is no substantial variation in the instantaneous electric field with angular position about the cathode. Other radial modes may be characterized by instantaneous potentials along the radius which start at zero in the periphery of the cavity resonator space, increase to a maximum in absolute value, decrease substantially to zero, and then increase to a high absolute value at the anode. Theoretically there may be any number of such maxima and substantially zero field points along a radius depending upon the radius of the cavity resonator used.

In order to minimize dielectric loss in the glass envelope walls it is desirous in some cases to operate at or near the harmonic of the free resonant frequency of the device in which case there will be more than one current loop in the circuit, and the tube walls which are sealed to the discs 4 and 5 may be placed at such a location in the system that they are removed from the voltage loops or at a point of minimum potential difference.

I have found at least one more important mode which is characterized by a dependence of the electric field structure in the cavity resonator upon the angular position about the cathode. In fact at any instant of time and progressing about the cathode axis in a circular path within the cavity resonator, the electric field starts at zero, increases first to a maximum, decreases to zero, changes polarity and decreases to a minimum in the opposite direction, then increases to zero at the point of beginning. I have found in this mode of oscillation that it is possible to attain a higher frequency with a given cavity resonator and to obtain greater power output at a given frequency of oscillation than is possible with the π mode. It is also possible to operate the tube in such a manner that in a circular path about the cathode in the cavity resonator the instantaneous field strength will be found to pass through two maxima and two minima or any even integral number of maxima and minima.

It will thus be seen that in the first mode of oscillation characterized by an angular dependence of the field strength that the number of electron groupings precessing about the cathode due to the magnetic field cannot be half the number of anode fingers but must be either one more or one less than half the number of fingers. Where the electron groupings are in proper phase to deliver energy to the anode there will be a maximum and a minimum in instantaneous field strength within the cavity resonator. The direction relative to the cathode in which the electric field strength within the cavity resonator is zero can conceivably move about in a perfectly symmetrical structure and would tend to do so upon insertion of a coupling loop so as to give a field configuration such that there would result an un-

favorable transfer of power to the coupling loop.

Power may be coupled out of the cavity resonator by any suitable device and I have illustrated in the drawings an arrangement for coupling out power which includes a loop which extends into an opening in the periphery of the cavity resonator. The coupling loop is inductively coupled to the magnetic field set up in the cavity resonator by the oscillations.

I therefore find it desirable to provide my electron discharge device with any suitable means so that the voltage and current loops may be provided in a predetermined location in the cavity resonator with this mode of operation and with respect to the position of the coupling loops and by placing the line to remove power at that portion of the cavity resonator where there is a relatively large change of magnetic flux, I will thereby be able to obtain an optimum transfer of power from the cavity resonator to the line.

Any suitable structural arrangement may be employed for producing this asymmetry and in Figs. 9, 10, and 11 I have illustrated three possible arrangements for producing this asymmetry. Thus in Fig. 9 I have illustrated the cathode 6a which has been displaced from its position of being substantially coincident with the longitudinal axis of the interdigitated anode or in other words the cathode 6a is shifted to the right as illustrated in Fig. 9. In Fig. 10 I have illustrated an arrangement for producing asymmetry which includes an anode construction in which the various fingers have substantially the same size and shape except one of the fingers 45 on one of the anode portions is longer or extends to a closer position to the ring 10a.

Another method of producing the asymmetry is illustrated in Fig. 11 in which one of the fingers 46 of one of the anode members is narrower than the other fingers. The forms in Figs. 9-11 involve a construction that departs in a predetermined manner from circular symmetry thus being circularly asymmetric. These disclosed forms are generally circularly symmetric. This symmetry is to be distinguished from endwise symmetry that may or may not be present.

It will be understood that many other types of mechanical asymmetry may be employed so as to predetermine the position of the voltage nodes and loops in the construction with respect to the power loop, such, for example, by providing the asymmetry in the external cavity resonator. Thus with a cavity resonator tuned by several radial screws spaced at 45° intervals and with the power output loop located in the 8th radial position, the power output of the device may be improved by withdrawing one or both of the screws 43a (indicated in Figure 13) on the cavity resonator diameter perpendicular to the radius passing through the coupling loop and such screws may be completely removed with resulting improvement in the power output in certain cases provided all the other screws are kept in substantially the same radial distance from the center of the cavity resonator.

Any suitable method or arrangement may be employed for positioning the power coupling loop with respect to the asymmetry of the device, the maximum change of magnetic field, or the current or voltage loops. Thus when the asymmetry is obtained by moving the cathode so that its axis is not in coincidence with the axis of the anode, the power coupling loop should be in line with the direction of movement of the cathode to produce the asymmetry. When the asymmetry is produced by two larger fingers di-

ametrically opposite each other, then the coupling loop should be perpendicular to a plane passing through the larger fingers. In any case the predetermined position of the coupling loop with respect to the asymmetry or the point of maximum change of flux or the point of the voltage node may be obtained by rotating the envelope within the cavity resonator until it attains that position with respect to the cavity resonator that a maximum or optimum amount of power is withdrawn through the coupling loop.

Although I have shown and described particular embodiments of my invention, I do not desire to be limited to the embodiments described, and I intend in the appended claims to cover all modifications which do not depart from the spirit and scope of my invention.

What I claim is:

- 20 1. An electron discharge device adapted to be connected to an encircling cavity resonator and to operate as a magnetron, comprising a cathode elongated along an axis, and anode means substantially all radial directions to said cathode, said anode means including continuous encircling terminal rings for connection to an encircling resonator, a pair of connectors about said cathode and a plurality of like axially extending conductors joined together in alternation by a respective one of said connectors, the foregoing construction being generally mechanically circularly symmetric about said axis and incorporating a circularly asymmetric structure.
- 25 35 2. An electron discharge device in accordance with claim 1 wherein said asymmetric construction is in the form of eccentricity of said anode means with respect to said cathode.
- 40 45 3. A magnetron including a cathode, anode means exposed in substantially all radial directions to said cathode and including a plurality of connectors about said cathode, a plurality of conductors extending from each of said connectors with the conductors on each connector interposed between the conductors on the other of said connectors, a cavity resonator encircling said anode means and joined to said connectors, and output coupling means penetrating said cavity resonator, said magnetron being capable of operation in a mode providing stationary nodal points spaced about said connectors, the foregoing construction incorporating a circularly asymmetric structure fixing said nodal points in relation to said output coupling means.
- 50 55 4. A magnetron including a cathode and coaxial anode means, said anode means including a pair of end connectors about said cathode and a plurality of like axially extending conductors spaced from each other and forming a cylinder, said conductors being joined alternately to a respective one of said end connectors, said conductors being alike in dimensions and mutual spacing, said anode means additionally including a distinctive conductor which is irregular in some way with respect to said like conductors.
- 60 65 5. A magnetron in accordance with claim 4 wherein said distinctive conductor is larger than the other conductors and positioned in said cylinder.
- 70 75 6. A magnetron in accordance with claim 4 wherein said distinctive conductor is longer than the other conductors and positioned in said cylinder.
7. A magnetron including coaxial anode and cathode means, said anode means including a

pair of circular connectors spaced axially apart and a plurality of like parallel conductive fingers spaced from each other and forming a cylinder, said fingers being joined in alternation to a respective one of said circular connectors, said fingers on each of said connectors extending toward the other connector and being alike in dimensions and mutual spacing, said anode means additionally including a conductor which is larger than said parallel conductive fingers, a cavity resonator encircling said anode means and joined to said circular connectors, and an output coupling element fixed in relation to said larger conductor.

8. A magnetron according to claim 3, wherein the circularly asymmetric structure is provided in the form of devices extending inwardly from the wall of said cavity resonator, certain of said devices extending further inwardly than the others.

9. A magnetron according to claim 3 wherein the circularly asymmetric structure is provided in the form of regularly spaced devices extending inwardly from the wall of said cavity resonator, said devices extending substantially equally except for a device spaced from said output coupling means by 90°.

10. A magnetron including a cathode elongated along an axis, and anode means surrounding said cathode, said anode means including a pair of circular connectors coaxial with and surrounding said cathode, said circular connectors being separated from each other axially, said anode means additionally having a plurality of axially extending conductors joined together in alternation by said circular connectors respectively, one of said axially extending conductors being different in width from the adjacent axially extending conductors.

11. A magnetron including a cathode, anode means exposed in substantially all radial directions to said cathode and including a plurality of connectors about said cathode, a plurality of conductors extending from each of said connectors with the conductors on each connector interposed between the conductors on the other of said connectors, a cavity resonator encircling said anode means and joined to said connectors, and output coupling means penetrating said cavity resonator, said magnetron being capable of operation in a mode providing stationary nodal points spaced about said connectors, the foregoing construction incorporating a circularly irregular structure fixing said nodal points in relation to said output coupling means.

12. A magnetron including a cathode and coaxial anode means, said anode means including a pair of end connectors about said cathode and a plurality of like axially extending conductors spaced from each other and forming a cylinder, said conductors being joined alternately to a respective one of said end connectors, said conductors being alike in dimensions and each substantially equally spaced from an adjacent one, said anode means additionally including a distinctive conductor which is irregular in some way with respect to said like conductors.

13. A magnetron in accordance with claim 12 wherein said distinctive conductor is larger than the other conductors and positioned in said cylinder.

14. A magnetron including coaxial anode and cathode means, said anode means including a pair of circular connectors spaced axially apart and a plurality of like parallel conductive fingers spaced from each other and forming a cylinder, said fingers being joined in alternation to a respective one of said circular connectors, said fingers on each of said connectors extending toward the other connector and being alike in dimensions and each substantially equally spaced from an adjacent one, said anode means additionally including a conductor which is larger than said parallel conductive fingers, a cavity resonator encircling said anode means and joined to said circular connectors, and an output coupling element fixed in relation to said larger conductor.

15. A magnetron including a cathode and coaxial anode means, said anode means including a pair of end connectors about said cathode and a plurality of like axially extending conductors spaced from each other and forming a cylinder, said conductors being joined alternately to a respective one of said end connectors, said conductors being alike in dimensions and each substantially equally spaced from an adjacent one, said anode means additionally including diametrically opposite conductors which are larger than said like conductors.

16. A magnetron including coaxial anode and cathode means, said anode means including a pair of circular connectors spaced axially apart and a plurality of like parallel conductive fingers spaced from each other and forming a cylinder, said fingers being joined in alternation to a respective one of said circular connectors, said fingers on each of said connectors extending toward the other connector and being alike in dimensions and each substantially equally spaced from an adjacent one, said anode means additionally including a pair of diametrically opposite conductors which are larger than said parallel conductive fingers, a cavity resonator encircling said anode means and joined to said circular connectors, and an output coupling element in said resonator in a plane perpendicular to the plane of said diametrically opposite larger conductors.
